UNITED STATES PATENT OFFICE.

NOEL BENOIT GALLAND, OF FEURS, FRANCE.

IMPROVEMENT IN PEN-HOLDERS.

Specification forming part of Letters Patent No. 147,930, dated February 24, 1874; application filed January 23, 1874.

To all whom it may concern:

Be it known that I, NOEL BENOIT GALLAND, of Feurs, in the Department of the Loire, France, have invented certain Improvements in Pen-Holders, of which the following is a specification:

My invention relates to certain improvements in pen-holders, the object of which is to overcome the difficulties experienced by young, weak, or aged persons in grasping and manipulating the pen, and also the inconvenience arising from the contact of the fingers, which are convex, with the pen-holder, which is also convex. The invention consists in a series of rings formed with collars for adjusting them on the pen-holder, so as to allow of the insertion of the fingers in the rings in any desired positions, thus relieving the fingers of the muscular strain which would otherwise be necessary.

In the accompanying drawing, Figure 1 is a perspective view of my invention, showing its application to the fingers. Fig. 2 is a side view of a pen-holder with four rings attached. Fig. 3 is a side view of a pen-holder with one ring attached. Fig. 4 is a transverse section taken in the line xx of Fig. 2. Fig. 5 is a transverse section taken in the line yy of Fig. 3. Figs. 6 and 7 are edge views of the rings.

Similar letters of reference indicate corresponding parts in all the figures.

A represents a pen-holder of any suitable construction and form, preferably cylindrical. B is a ring made of sheet metal, with a collar, b , formed on one portion of its periphery. The ring is of such dimensions as to fit one of the fingers, and the collar corresponds with the

size of the pen-holder. The ring and collar are made of one strip of metal, either bylapping and soldering the ends, as shown in Fig. 6, or by forming the collar at one end and bending the remaining portion to form the ring, as shown in Fig. 7.

The invention is applied to the pen-holder by inserting it through the collar b , and then adjusting the ring to suit the finger. There may be a single ring used, for the forefinger only, as shown in Fig. 3, or two, three, or four, as shown in Figs. 1 and 2. When four rings are used, the ring B^2 surrounds the forefinger between the second and third joints, the ring B^1 surrounds the tip of the forefinger, while the thumb engages with the ring B^3 , and the second or middle finger with the ring B^4 , as shown in Fig. 1.

By means of this invention the fingers are brought in contact with a concave surface, giving more ease and comfort than the convex surface of the bare pen-holder, and there is no muscular exertion necessary in grasping or manipulating the pen, the only resistance to be overcome being the friction of the pen upon the surface of the paper.

What I claim as new, and desire to secure by Letters Patent, is—

The adjustable ring or rings, formed with the collars b for adjusting them on the pen-holder to allow the insertion of the fingers into said rings in any desired position, substantially as described, for the object set forth.

GALLAND.
